UNITED STATES PATENT OFFICE.

JOHN P. CHRISTENSEN, OF SAN DIEGO, CALIFORNIA.

IMPROVEMENT IN BUCKETS FOR WINDLASS WATER-ELEVATORS.

Specification forming part of Letters Patent No. 146,315, dated January 13, 1874; application filed June 17, 1873.

To all whom it may concern:

Be it known that I, J. P. CHRISTENSEN, of San Diego city and county, State of California, have invented Improvements in Water-Elevators; and I do hereby declare the following description and accompanying drawings are sufficient to enable any person skilled in the art or science to which it most nearly appertains to make and use my said invention or improvement without further invention or experiment.

My invention relates to an improved bucket, to be used in connection with that class of water-elevators in which two or more buckets are attached to an endless chain, and the chain operated by a pulley to raise and lower the buckets.

In order to more fully illustrate and explain my invention, reference is had to the accompanying drawings forming a part of this specification, in which—

Figure 1 is a perspective view of one of the buckets. Fig. 2 is a side elevation, showing a section of one of the buckets.

A represents a bucket, having one side attached to a chain, b. The end e of this bucket is constructed in the manner of an inclined plane, as shown, thus making the side d, opposite the chain b, longer than the side to which the chain is attached. The side is open at f, opposite the inclined end piece, as shown, so as to provide an opening through which the bucket is filled and emptied, the inclined end serving as a spout to direct the water

when the bucket is being emptied. A tube, e, which can either be attached to the bucket or form a fixed part of it, extends from the lower or square end of the bucket up over the end of the side d, and thence down inside of the bucket to near the bottom. The opposite ends of this tube are open, and a hole, i, is made through it at the point where it bends over the end d, so as to prevent it from acting as a siphon, and thus emptying the bucket before it is intended to be emptied. The object of this tube is to allow the air to escape from the interior of the bucket when it is being filled; otherwise the air in the vessel would prevent the entrance of the water, and the bucket would be inoperative. As the bucket reverses its position at the bottom of the well in passing around with the chain, it is filled with water, and when it has been drawn up out of the well it will be emptied when the bucket tips in passing over the upper pulley, the inclined end serving as a spout.

Having thus described my invention, what I claim, and desire to secure by Letters Patent, is—

The bucket A, constructed as described, in combination with the pipe e, having hole i, as and for the purpose set forth.

In witness whereof, I hereunto set my hand and seal.

JOHN PETER CHRISTENSEN. [L. S.]
